UNITED STATES PATENT OFFICE.

WARREN H. SHAY, OF TOLEDO, OHIO, ASSIGNOR OF ONE-HALF TO RALPH SHAY, OF SAME PLACE.

CAN-OPENER.

SPECIFICATION forming part of Letters Patent No. 470,710, dated March 15, 1892.

Application filed June 25, 1891. Serial No. 397,469. (No model.)

To all whom it may concern:

Be it known that I, WARREN H. SHAY, of Toledo, county of Lucas, and State of Ohio, have invented certain new and useful Improvements in a Compound Tool; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to a compound tool, and has for its object to provide a handle to which may be attached a wire for forming a can wrench or holder and with provision for attaching a cutter to form a can-opener.

A further object is to form the pivotal center of the knife-lever adjustable radially.

A further object is to provide for a radial adjustment of the knife.

The invention consists in the parts and combination of parts hereinafter described, and pointed out in the claims.

In the drawings, Figure 1 is a plan view of a combined can wrench or holder and can-opener. Fig. 2 is a perspective view of the handle and adjustable center for the can-opener pivot. Fig. 3 is a plan view of the clamping-wire. Fig. 4 is a side elevation of the knife-lever. Fig. 5 is an enlarged transverse sectional view of the knife-lever and knife-bar, showing the knife in full lines; and Fig. 6 is a longitudinal vertical section through the center of the handle with the front half removed.

1 designates the handle, formed with a curved projection 2 to bear against the can, 40 and a hook projection 3, which is engaged with loop end 4 of a clamping-wire 5. The clamping-wire is bent in circular form and has an end portion 6 running parallel with the body of handle 1, whereby the handle 45 and wire may be grasped in the hand, and by forcing the wire toward the handle the area of the circle is decreased, thereby impinging the wire upon the outer surface of the can and forcing the same frictionally against 50 the curved projection 2 of the handle suffi-

ciently to hold the can from turning, or, if used as a wrench, holding the top of the can firmly while unscrewing the same.

In order to convert the tool into a can-opener, I form the handle with a longitudinal slot 55 7, through which is passed the reduced screw-threaded end 8 of a pin 9, the head of the pin being enlarged to prevent the same from passing through the slot as the pin is introduced from the bottom side of the handle. The front 60 cross-bar 10 of the handle, which extends across the slot, is formed with a rib 11, there being, preferably, an intermediate cross-bar 12 to prevent the metal on each side of the slot from springing when the handle is grasped. 65

13 designates a longitudinally-movable pivot-bar formed with a downwardly-projecting guide-pin 14 at the rear end, which enters slot 7 and moves freely therein, and also with serrations 15 upon the front end, into which the 70 rib 11 enters when the bar is properly adjusted, the bar being held in adjustment by pin 9, which passes through a perforation formed in the bar by means of a nut 15', run upon the projecting end and bearing upon 75 the upper side of the bar. The outer end of the pivot-bar is formed with a perforation 16 to receive a pivot-pin 17, projecting vertically from the outer end of a cutter-lever 18. Lever 18 has a flat body portion 19, having a slot 20 80 formed longitudinally thereof, through which is passed a screw-threaded pin 21, secured to a knife 22, there being a thumb-nut 23 run upon pin 21 to hold the same to any desired adjustment upon the knife-lever. The outer 85 end of the knife-lever is provided with a handle 24, by which to operate the same.

In operation, if it is desired to unscrew the top of a can, loop 4 of clamping-wire 5 is engaged with hook 3 of the handle, the wire is 90 caused to embrace the top of the can, when the handle and end 6 of the wire are grasped, and the top is firmly held by the wrench while unscrewing the same.

To convert the tool into a can-opener—that 95 is, for tin cans in which fruit, &c., is hermetically sealed—the pivot-bar 13 is extended to a degree to cause the perforation therein to coincide with the center of the can. Pin 17 of lever 18 is now introduced into the perfo- 100

ration and knife 22 is adjusted by means of the thumb-screw, so that it will enter the top of the can near the margin, when by grasping the handle of the lever and forcing the knife 5 through the top of the can, and then moving the knife-lever circumferentially with respect to its pivot, a circular disk is cut either partially or entirely from the top, as it is only necessary in order to cut the top entirely from 10 the can to release the frictional hold upon the can and move the wrench or holder to another position upon the can to complete the cut.

It will be understood from the foregoing description that the device is not only simple 15 and inexpensive but that it is adaptable to cans of various sizes by reason of the expansibility or contractibility of the arc of a circle described by the wire and the adjustability of the pivot-bar and knife.

20 In some forms of tools where the cans are of uniform diameter I may cast the pivot-bar integral with the handle and form the knife either solid with or adjustable upon the knife-lever.

25 What I claim is—

1. In a compound tool, a handle formed with an integral curved projection to bear against the can and an oppositely-disposed curved projection having a reversibly-curved 30 hook, in combination with a clamping-wire formed with a loop end to engage the hook,

said wire having a circular portion to embrace the can and an end portion in parallel relation with the body of the handle.

2. In a compound tool, a handle formed 35 with oppositely-disposed arms, a clamping-wire connected with one arm, having a body portion to embrace an object and an end portion in substantially parallel relation with the body of the handle, a bar connected with the 40 handle, having an end portion projecting beyond the arm of the handle, and a lever pivotally connected with the bar and carrying a cutter.

3. In a compound tool, a handle formed 45 with oppositely-disposed arms, a clamping-wire connected with one arm, having a body portion to embrace an object and an end portion in substantially parallel relation with the body of the handle, a bar adjustably connected with the handle, having an end portion projecting beyond the arm of the handle, and a lever pivotally connected with the bar and carrying an adjustable cutter.

In testimony that I claim the foregoing as 50 my own I hereby affix my signature in presence of two witnesses.

WARREN H. SHAY.
